UNITED STATES PATENT OFFICE.

JOHN F. BUDKE, OF CANONSBURG, PENNSYLVANIA.

CRATE FOR ROLLS.

SPECIFICATION forming part of Letters Patent No. 693,104, dated February 11, 1902.

Application filed February 13, 1901. Renewed November 22, 1901. Serial No. 83,301. (No model.)

To all whom it may concern:

Be it known that I, JOHN F. BUDKE, a citizen of the United States, residing at Canonsburg, in the county of Washington and State 5 of Pennsylvania, have invented or discovered certain new and useful Improvements in Crates for Rolls, of which improvements the following is a specification.

The invention described herein relates to 10 certain improvements in racks for the removal of rolls from their housings and storing said rolls while not in use.

The invention has for its object a construction whereby both rolls may be simultaneously removed from and placed in their housings and whereby the rolls of each pair may be kept together while not in use and in proper position for their arrangement in the housing when required.

20 The invention is hereinafter more fully described and claimed.

In the accompanying drawings, forming a part of this specification, Figure 1 is a perspective view showing a pair of rolls supported 25 by my improved rack, and Fig. 2 is a sectional elevation showing the manner of using the rack or frame in removing rolls from their housings.

In the practice of my invention the rack is 30 formed of two horizontal or supporting members and two pairs of vertical or retaining members at least, one pair of the retaining members being pivotally connected to the supporting members, and means for holding 35 the vertical members in retaining position. Each of the horizontal or supporting members can be conveniently formed of two rails or bars 1, between which are secured one of each pair of retaining members 2 and 3. One of 40 the members, as 2, is preferably secured in a vertical position between the rails or bars 1, while the other member 3 is pivotally held in place between the rails or bars 1, so that it can be turned down into alignment with the 45 rails or bars.

In using the rack to remove rolls from housings the pivotal members 3 are turned down into alignment with the supporting members. The pivotal and supporting members are then 50 pushed under the lower roll until the rigid vertical members 2 bear against the rolls, as shown in Fig. 2. The pivotal members 3 are

then turned up against the rolls and secured in such position either by means of loops 4, pivotally connected to the members 2 or 3 and 55 adapted to be turned down to engage the other member, or by means of a rod or key 5, adapted to be interposed between shoulders 6 on the members 3 and the horizontal supporting members when the members 3 are turned up, as 60 shown in Fig. 1. One or both of these locking devices may be used. The key or rod 5 is preferably held in position by means of hooks 7, mounted on the horizontal supporting members. After the rack has been placed 65 in position it is raised by any suitable means, such as a crane, by which the rolls are to be removed from the housings, or by driving wedges 8 between the horizontal supporting members and the housing-shoes 9, as shown 70 in Fig. 2, thereby lifting the journals of the rolls from their bearings. The holding-screws of one of the housings is then loosened and that housing slid along the shoes 9 sufficiently far to permit the rolls to be swung clear of 75 the housing.

It is preferred to employ a frame substantially such as shown for connecting the rack to the lifting-crane. The rack consists of two parts or arms 10, connected by a bar or 80 plate 11, to which is attached a hook or eye 12. Each of the arms is provided with two movable hooks 13, adapted to engage loops 14 on the vertical posts or members 2 and 3 of the rack. These arms 10 can be conveniently formed by two rails secured parallel with each other, as shown in Fig. 1. The hooks are provided with heads or enlargements 15, which are movable along the flanges of the rails forming the arms, so as to bring the 90 hooks into alignment with the posts or members 2 and 3. By the employment of the lifting-frame with adjustable hooks the strains incident to lifting the rolls will be in line with the vertical posts or members 2 and 3, thus 95 avoiding all liability of twisting or bending the latter.

The horizontal or supporting members are adjustably connected together by rods 16, so that the same rack can be used with different 100 lengths of rolls.

After removing the rolls from the housings they can be transferred to the roll-turning shop or to the place of storage. The rolls

should be kept in the racks while in storage, thus preventing the separation of the rolls of a pair.

I claim herein as my invention—

- 5 1. A portable rack for rolls, having in combination, a supporting member, a pair of posts secured to the supporting member and adapted to retain the rolls in position one upon the other and on the supporting member, one of the posts being pivoted to the supporting member and adapted to be turned down into alinement therewith, substantially as set forth.
- 10 2. A portable rack for rolls, having in combination, supporting members and two pairs of posts secured to the supporting members and adapted to retain the rolls one upon the other and on the supporting members, one pair of posts being pivotally connected to the supporting members and adapted to be turned down into alinement therewith, substantially as set forth.
- 15 3. A portable rack for rolls, having in combination, supporting members and two pairs of posts secured to the supporting members and adapted to retain the rolls one upon the other and on the supporting members, one pair of posts being pivotally connected to the supporting members and adapted to be turned down into alinement therewith, substantially as set forth.

3. A rack for rolls having in combination two supporting members adjustably connected together, and two pairs of posts secured to the supporting members and adapted to retain the rolls in position, one pair of posts being pivotally connected to the supporting members, substantially as set forth. 25

4. The combination of two roll-supporting members adjustably connected together, two pairs secured to the supporting members and adapted to retain the rolls in position, one pair of posts being pivotally connected to the supporting members, a lifting-frame and 30 hooks adjustably mounted on the frame and adapted to engage the retaining-posts, substantially as set forth. 35

In testimony whereof I have hereunto set my hand.

JOHN F. BUDKE.
